UNITED STATES PATENT OFFICE.

WILFRED B. CARTLEDGE, OF ATTLEBOROUGH, MASSACHUSETTS, ASSIGNOR
TO THE W. H. WILMARSH & COMPANY, OF SAME PLACE.

MACHINE FOR MAKING CURB-CHAINS.

SPECIFICATION forming part of Letters Patent No. 628,439, dated July 4, 1899.

Application filed November 23, 1898. Serial No. 697,289. (No model.)

To all whom it may concern:

Be it known that I, WILFRED B. CARTLEDGE, a citizen of the United States, residing at Attleborough, in the State of Massachusetts, have invented a new and useful Improvement 5 in Machines for Making Curb-Chains, of which the following is a specification.

The object of my invention is to provide a machine of simple and compact structure 10 adapted for the manufacture of curb-chain; and it consists in the improved construction and arrangement of parts, as hereinafter fully set forth.

In the accompanying drawings, Figure 1 represents a top view of the machine. Fig. 2 represents a vertical section taken in the line 2 2 of Fig. 1. Fig. 3 represents a section taken in the line 3 3 of Fig. 1. Fig. 4 represents a detail top view showing the link-forming tools when in a position differing from that shown in Fig. 1. Fig. 5 represents a detail top view with the link-forming tools in another position. Fig. 6 represents the link-forming tools with the completely-twisted 25 link between them. Fig. 7 represents a side view of the cam for clamping the feed-wire. Fig. 8 represents a side view of the cam for feeding the wire forward to the machine. Fig. 9 represents a view of that portion of the 30 cam shown in Fig. 8 which causes the forward movement of the wire. Fig. 10 represents a side view of the cam which actuates the cutter for severing the wire to form the blank. Figs. 11, 12, and 13 represent different views 35 of the tool for closing the end of the link and for twisting the link. Figs. 14, 15, and 16 represent different views of the vertically-reciprocated mandrel upon which the link is shaped. Figs. 17, 18, and 19 represent different 40 views of the tool for bending the wire of the link around the mandrel.

In the accompanying drawings, A represents the bed of the machine, B the driving-shaft, which is connected with the oppositely-located parallel shaft B' by means of the intermediate shaft C and the miter-gears a a and b b. Upon the shaft B are secured the cam D, which by means of the lever E serves to feed the wire c forward, and the cam F, 45 which by means of the lever G serves to clamp the wire c in its forward position for

the action of the cutter H, which is actuated by the cam I, secured to the shaft B'. The bending-tool J, by means of which the severed piece of wire is bent around the mandrel 55 K, is caused to reciprocate by means of the cam L, secured to the shaft B, and the reacting spring d, the wire in its initial bending being guided by the notches e e, made in the projecting horns e' e' of the tool J. The mandrel K, upon which the link is bent and closed, is provided with the vertical groove f, as usual in chain-machines, but having an oblique notch f' formed at one side of the said groove, as shown in Figs. 14 and 15, the said notch 65 being adapted to receive the edge of the twisted link g, as shown by the link in Fig. 15, the said link being supported in this position by means of the wire c, as shown in Figs. 1 and 2. The mandrel K is operated for up-and-down movement by means of the cam N upon the shaft B' acting upon the roller h to cause the downward movement of the lever O, which at its outer end carries the sliding spindle P, which supports the mandrel K, the 70 upward movement being imparted to the spindle by means of the spiral spring Q.

The tool R, by means of which the link is closed around the mandrel and subsequently twisted to form a curb-link, is reciprocated by 80 means of the cam S upon the shaft B' and the spiral spring T, and the required partial rotation of the tool R is effected by means of the gear-pinion U, the sliding rack U', the cam V upon the shaft C, and the spiral spring V'. 85

The bending-tool J is provided with a recess i, adapted to receive a portion of the previously-formed link g of the chain, and with the inwardly-projecting ledges j and j', which are adapted to hold one end of the link 90 at opposite sides while the opposite end is being turned by the partial rotation of the tool R to twist the link, the said tool R being provided with the curved groove k, adapted to firmly hold the closed end of the link while 95 the link is being twisted, and with the outwardly-flaring grooved surfaces m m, which serve to incline the spread ends of the initially-bent link inwardly to the curved central portion k, the said grooved construction 100 being shown in Fig. 11 and indicated by the dotted line in the side view, Fig. 12.

The operation of the machine will be as follows: The wire *c* is fed forward by means of the action of the cam *D* upon the lever *E* and is clamped in its forward position by the action of the cam *F* upon the lever *G*, while the cutter *H*, which serves to sever the initial blank from the clamped wire *c*, is actuated by means of the cam *I*, the said parts for forming the initial blank being of old and well-known construction. When the wire blank has been severed from the wire *c* by the action of the cutter *H*, the bending-tool *J* is brought forward by the action of the cam *L*, the wire blank in its initial bending being held in the supporting-notches *e e'*, made in the projecting horns *e' e'* of the tool *J*, the previously-formed link *g* of the chain being at the same time supported by the wire *c* or by the severed wire blank and held in the groove *f* and notch *f'* of the mandrel *K*, as shown in Figs. 1 and 2. When the wire blank *c'* has been bent around the mandrel *K*, as shown in Fig. 4, the link-closing tool *R* is brought forward by the action of the cam *S* to close the ends of the blank *c'* upon the mandrel *K*, as shown in Fig. 5, and upon the closure of the said ends the mandrel is carried downward from the link by means of the action of the cam *N* upon the lever *O*, to which the mandrel is connected by means of the sliding spindle *P*. The closed end of the link being now held firmly in the closely-fitting curved groove *k* and the opposite bent end of the link being prevented from turning in the bending-tool *J* by means of the ledges *j* and *j'*, a partial rotation is imparted to the closing and rotative tool *R* by the action of the cam *V* upon the sliding rack *U'*, and upon the twisting of the link the tools *J* and *R*, with the twisted link between them, are actuated by their respective cams to carry the link to a backward position, in which the wire *c* may be fed through the opening of said link, as shown in Fig. 6. The tools *J* and *R* are then carried by their actuating-springs back to their rearward position, releasing the completed link *g* upon the forwardly-fed wire *c*, as shown in Fig. 1, and then the mandrel *K* is brought up by the action of the spring *Q* at the back of the previously-formed link *g* and the wire *c*, as shown in Figs. 1 and 2, and the continuous operation of the machine will add successive twisted links to the chain *W*.

55 I claim as my invention—

1. In a chain-machine, the combination of the bending-tool provided with the recess for receiving a portion of the previously-formed link, and the projecting ledges adapted to bear upon opposite sides of the bent end of the link to prevent the rotation of the same in one direction, and the rotative tool provided with the flaring grooved surfaces and the intermediate curved groove, whereby the open end of the link will be closed and then properly held in a fitting-groove while the link is being twisted by the said rotative tool, and means for causing the partial rotation of the said tool to twist the link, substantially as described.

65 70

2. In a chain-machine, the combination of the mandrel, and means for imparting an up-and-down movement thereto, with the bending-tool adapted to bend the wire blank around the mandrel, and provided with the ledges projecting inwardly at opposite sides and adapted to hold the bent link while it is being twisted in one direction, means for actuating the bending-tool, the rotative tool provided with the curved groove at its face, 80 and the flaring grooved surfaces, means for causing the rotative tool to close the ends of the link around the mandrel, and means for imparting partial rotation to the rotative tool upon the withdrawal of the mandrel from the link, substantially as described.

3. In a chain-machine, the bending-tool provided with the notched horns for holding the wire blank after it has been cut off and while it is being bent around the mandrel, and the inwardly-projecting ledges adapted to prevent the rotation of the bent end of the link while the link is being twisted, and the recess for receiving a portion of the previously-formed link, substantially as described.

90 95 100 105 110 115

4. In a chain-machine, the combination of the mandrel, with the bending-tool adapted to bend the blank around the mandrel and hold the bent link while it is being twisted, the rotative tool provided with a curved groove on its face, means for causing the forward movement of the bending-tool and the rotative tool, to bend and close the link around the mandrel, means for removing the mandrel from the bent and closed link, means for causing the partial rotation of the rotative tool to twist the link, means for causing the backward movement of the bending-tool and the corresponding forward movement of the rotative tool with the inclosed link to a rearward position for receiving the wire for the formation of another link, and means for raising the mandrel in front of the wire, upon the withdrawal of the bending and rotative tools from the link, substantially as described.

120 125

5. In a chain-machine, the rotative tool provided with the flaring grooved surfaces, and the intermediate curved groove adapted to fit the form of the closed end of the link, and serve to hold the same while the link is being twisted by the partial rotation of the tool, substantially as described.

WILFRED B. CARTLEDGE.

Witnesses:

JOHN W. SUTTON,
ROBERT E. HARRIS.

It is hereby certified that the assignee in Letters Patent No. 628,439, granted July 4, 1899, upon the application of Wilfred B. Cartledge, of Attleborough, Massachusetts, for an improvement in "Machines for Making Curb-Chains," should have been described and specified as the *W. H. Wilmarth & Co., Corporation*, instead of the "W. H. Wilmarth & Company;" and that the said Letters Patent should be read with this correction therein that the same may conform to the record of the case in the Patent Office.

Signed, countersigned, and sealed this 22d day of August, A. D., 1899.

[SEAL.]

WEBSTER DAVIS,
Assistant Secretary of the Interior.
